LAUNDRY PRESSING IRON

William M. Cissell, Jefferson County, Ky.

Application November 23, 1937, Serial No. 176,000

10 Claims. (Cl. 38—77)

This invention relates to flat, sad and pressing irons equipped with a heating element and means for dispensing steam on the material under treatment.

An object of the invention is to provide a pressing iron of the indicated character having highly improved means for receiving steam from an external supply, conditioning the steam received within the iron, and then discharging the conditioned steam onto material being pressed; the conditioning consisting of retarding the flow of the steam as it passes through the iron per se, removing condensate from the steam, converting the condensate into steam, and regulating the humidity of the steam discharged upon the material being pressed.

A further object of this invention is to provide a pressing iron of the indicated character, having means for steaming and drying in a single pressing operation, whereof materials can be pressed and steamed or dried in one motion of the pressing iron, so that the operator's time and capacity is utilized more efficiently.

A further object resides generally in the sturdy and simple construction of the pressing iron and its accessories, whereof it can be readily manufactured and easily maintained.

With the above and other objects in view, as will be hereinafter apparent, the invention consists in the utilization of certain novel principles, the details of construction and combination of parts hereinafter fully described and illustrated in the accompanying drawing and specifically claimed.

Figure 1 is a perspective view of a pressing iron embodying the invention.

Figure 1A is an enlarged sectional view of air injector sub-assembly, indicated as conduit 15 in Figure 1.

Figure 2 is a plan view of the iron per se as shown in Figure 1 after the entire handle, cover, piping, ridges and air injector have been removed.

Figure 3 illustrates the bottom or face of the iron without the projecting accessories.

Figure 4 is a sectional view of the iron along line 3—3 of Figure 1.

Figure 5 is a fragmentary plan view of the forward end of the iron showing a modified mounting for the air injector and fluid dispenser.

Figure 6 is a perspective view, on an enlarged scale, of the air injector and fluid dispenser employed in Figure 5.

Numeral 10 designates the sole plate of the iron, 11 the cover, 12 the handle, 13 the fore support, and 14 the rear support for the handle 12.

A fluid chamber 101 is formed in the forward portion of the sole plate, which chamber is closed except for an inlet conduit 15, outlet holes 102, and a marginal outlet slit 103. The complete details of conduit 15 are not shown in Figure 1, since this may be either a part of the sole plate, or a metallic or asbestos compound pipe. However, a preferred structure is shown in Figure 1A in which 150 is a pipe body having an enlarged head 151 from which a nozzle 152 and an air channel 153 extend; the two latter elements leading into conduit 15. In cap 154 the plurality of holes 155 admit air, while the elbow 16 serves to connect conduit 21 with nozzle 152 for discharging a jet of conditioned steam into chamber 101 via conduit 15. Thus it will be perceived that air is drawn through holes 155 and mixed with the steam for reducing the temperature of the latter. It should be noted, although not shown by the drawing in full detail, that cap 154 can be rotated to control the area of air opening in communication with the air channel. This is effected by rotating cap 154 and one or more of the openings 155 out of register with a semi-circular slot in the head 151.

Numeral 20 designates a nipple through which steam is received and delivered to conduit 104 for treatment as fully explained in United States Patent No. 1,799,281 issued April 7, 1931, to William M. Cissell. Therefore, it is sufficient to state that this conduit is suitably constructed and equipped with means 104b for separating, trapping and retaining condensate until evaporated, for the purpose of eliminating free water from the steam discharged onto the material being pressed, and thus prevent spotting thereby.

Conduit 21 is preferably fixedly connected to the discharge end of conduit 104, as shown in Figure 2, and receives dry steam at a temperature in excess of that required. Therefore, as a direct and efficacious means for dissipating a portion of this heat, the outlet of conduit 21 is connected to conduit 15 through elbow 16, and the conduit 21 is provided with a series of metallic radiating discs 22 to produce a relatively high capacity heat dissipator or exchanger in order that material quantities of heat can be dissipated. Obviously proportioning the heat exchanger will control the temperature of steam as desired.

As a means for further reducing the temperature of the steam before delivery to chamber 101, where it is again momentarily subjected to high heat, air is drawn into the air channel 153, as explained above in terms of Figure 1A, to prevent the fluid mixture of steam and air from

attaining an undesired high temperature before discharge from apertures 102 and slit 103. In Figure 4, the slit is shown disposed at an angle to the vertical, with the slit per se disposed above the face of the iron, so that the dispensed fluid is freely discharged onto the material under treatment and thereby effect partial condensation before contacting said material. It will be obvious that these openings can be varied as to magnitude, location or combination, to dispense the fluid for attainment of results within the range of this pressing iron. The ridges or perches 106 are provided for supporting and/or receiving a conventional heater element 107, also for attachment of accessories after conventional practice.

From the foregoing description of Figs. 1, 1A, 2 and 3, it will be apparent that the steam received in conduit 104 is super-heated by the heating element 107 associated with the sole plate 10. Likewise, by reason of the water trapping means 104b disposed within conduit 104 in accordance with the teachings of my said earlier United States Letters Patent No. 1,799,281 issued April 7, 1931, all free-water carried in the steam received in the conduit 104 is converted into steam. Thus, the steam leaving conduit 104 via conduit 21 is super-heated, dry, and free of all free-water. Since the relative humidity of this super-heated steam is very low, and the temperature thereof is in excess of that required, a radiator or heat exchanger 22 is included in the conduit 21 for reducing the temperature of the steam flowing therethrough. Obviously, any reduction in the temperature of the steam increases the relative humidity thereof.

Accordingly, for further reducing the temperature of the steam flowing from the conduit 21 into chamber 101, a mixing conduit 15 is connected between the conduit 21 and the chamber 101, which mixing conduit is provided with a steam nozzle 152 and a rotatable cap 154 for regulating the amount of air drawn through the openings 155 into the air channel 153 by reason of the suction created within the mixing conduit in response to the steam discharged from the nozzle 152. As mentioned hereinbefore, regulating the amount of air mixed with the steam directly regulates its temperature and humidity.

Therefore, mixing air with the super-heated steam in the immediate vicinity of the work, reduces the temperature thereof and converts the steam into a relatively wet steam, free of any globules of free water, which steam has a saturated vapor content sufficient to provide the required moistening of the work without spotting.

The advantages of such an arrangement include variable control of vapor content and consistent performance, neither of which can be accomplished by directly using the steam from the supply line. Obviously, the steam from the supply line is highly variable and unsuitable, by reason of water of condensation being carried with the steam as globules of free water. Hence, in the present embodiment, the steam is super-heated to a temperature much in excess of that required for the steam, so as to remove positively all traces of free-water, and to convert all moisture into vapor thoroughly diffused in the steam. The temperature of the steam is then reduced in the immediate vicinity of the work to provide a moist steam having a high vapor content. Thus, the moist condition of the steam

discharged upon the work is accurately determined in the immediate vicinity of the work irrespective of the irregularities that may occur in the quality of the steam delivered from the steam supply line to the steam inlet 20.

In the modification shown in Figure 5 the heat exchanger 22 has been eliminated, and a short conduit 25 substituted for the long one 21. Conduit 25 is similarly attached to conduit 104 in the sole plate 10, and adjustably terminates in an arm 26, which conduit forms the latter's sole support. When coupling nut 260 is loose, said arm can be adjusted to a selected position. This arm is similar in principle to the structure shown in Figure 1A. However, there is no counterpart to cap 154, as air channels 153 and 263 are substantial equivalents, likewise conduits 15 and 261 are practical equivalents. Nozzle 264 has been disposed adjacent the "nose" or remote end of sole plate 10 so as not to drag on the material under treatment. Since arm 26 is adjustable, i. e. rotatively attached to conduit 25, it can be swung as desired for delivery of the fluid in advance of the iron as it travels during a forward pressing operation.

It is to be understood that changes from the invention may be made within the scope of what is claimed, without departing from the spirit of the invention.

I claim:

1. A pressing iron, comprising a sole plate having an internal steam conduit; an external arm adjustably mounted on the iron and having a dispensing chamber formed therein; a nozzle leading therefrom; said dispensing chamber having an air intake formed therein; a steam inlet communicating with the internal conduit, and an external conduit connecting said internal conduit with said chamber.

2. A pressing iron, comprising; a sole plate having an internal steam conduit constituting an expansion chamber in the form of a tortuous path for supplied steam; a heating element associated with said plate; an external arm having a short dispensing chamber formed therein and open to the atmosphere and a nozzle leading therefrom; a steam inlet communicating with the internal conduit; and an external conduit connecting said internal conduit with said dispensing chamber, said arm being mounted on and carried by said external conduit.

3. A steam-dispensing pressing-iron having in combination, a conduit within which steam employed in the operation of the iron is treated, said conduit having an inlet for receiving condensate-laden steam and an outlet for delivering treated steam onto the surface of material being pressed by the said iron; means operatively associated with the said conduit for arresting condensate from the said steam; a heating element operatively associated with the arresting means for converting the arrested condensate into steam; and a heat exchanger exposed to the atmosphere and operatively associated with the outlet of the said conduit for reducing the temperature of the treated steam and converting the same into a relatively moist steam.

4. A steam-dispensing pressing-iron having in combination, a conduit within which steam employed in the operation of the iron is treated, said conduit having an inlet for receiving condensate-laden steam and an outlet for delivering treated steam onto the surface of material being pressed by the said iron; means operatively associated

with the said conduit for arresting condensate from the said steam; a heating element operatively associated with the arresting means for converting the arrested condensate into steam; and means operatively associated with the outlet of the said conduit and activated by the flow of said steam for admitting air into the treated steam, to reduce the temperature of the treated steam and to convert the same into a relatively moist steam.

5. A steam-dispensing pressing-iron having in combination, a conduit within which steam employed in the operation of the iron is treated, said conduit having an inlet for receiving condensate-laden steam and an outlet for delivering treated steam onto the surface of material being pressed by the said iron; means operatively associated with the said conduit for raising the temperature of the steam received therein and converting the same into a relatively dry steam; and means operatively associated with the outlet of the said conduit for reducing the temperature of the treated steam and converting the same into a relatively moist steam.

6. A steam-dispensing pressing-iron having in combination, a conduit within which steam employed in the operation of the iron is treated, said conduit having an inlet for receiving condensate-laden steam and an outlet for delivering treated steam onto the surface of material being pressed by the said iron; means operatively associated with the said conduit for arresting condensate from the said steam; heating means operatively associated with the arresting means for converting the arrested condensate into steam; and means operatively associated with the outlet of the said conduit for admitting a quantity of air into the treated steam, to reduce the temperature of the treated steam and convert the same into a relatively moist steam.

7. A steam-dispensing pressing-iron having in combination, a conduit within which steam employed in the operation of the iron is treated, said conduit having an inlet for receiving condensate-laden steam and an outlet for delivering treated steam onto the surface of material being pressed by the said iron; means operatively associated with the said conduit for arresting condensate from the said steam; heating means operatively associated with the arresting means for converting the arrested condensate into steam; and means operatively associated with the outlet of the said conduit for reducing the temperature of the treated steam and converting the same into a relatively moist steam.

8. A steam-dispensing pressing-iron having in combination, a conduit within which steam employed in the operation of the iron is treated, said

conduit having an inlet for receiving condensate-laden steam and an outlet for dispensing steam treated within the said conduit; an arm disposed externally having an outlet for delivering treated steam onto the surface of material being pressed by the said iron; means operatively connecting the outlet of the said conduit and the outlet of the said arm for conducting treated steam from the outlet of the said conduit to the outlet of the said arm; means operatively associated with the said conduit for arresting condensate from the said steam; heating means operatively associated with the arresting means for converting the arrested condensate into steam; and means operatively associated with the outlet of the said conduit for reducing the temperature of the treated steam and converting the same into a relatively moist steam.

9. A steam-dispensing pressing-iron having, in combination, a conduit within which steam employed in the operation of the iron is treated, said conduit having an inlet for receiving untreated steam containing water of condensation entrained therein and an outlet for discharging treated steam onto the surface of material being pressed by the said iron; heating means operatively associated with the said conduit for super-heating the untreated steam and all entrained water of condensation received therein, to convert the same into a relatively dry super-heated steam; and cooling means operatively associated with the said conduit between the heating means and the outlet of the conduit for reducing the temperature of the super-heated steam and converting the same into a relatively moist steam.

10. A steam-dispensing pressing-apparatus having, in combination, a conduit within which steam employed in the operation of the apparatus is treated, said conduit having an inlet for receiving untreated steam containing water of condensation entrained therein and an outlet for the treated steam; heating means operatively associated with the said conduit for super-heating the untreated steam and all entrained water of condensation received therein, to convert the same into a relatively dry super-heated steam; cooling means operatively associated with the said conduit between the heating means and the outlet of the conduit for reducing the temperature of the super-heated steam and converting the same into a mist of relatively moist steam; and means operatively associated with the outlet of the said conduit for discharging the aforesaid mist onto the surface of material being pressed by the said apparatus before the moisture can settle out of the mist as a condensation precipitate.

WILLIAM M. CISSELL.
